DESIGN FOR AN ENSEMBLE DRESS

Mary Mullen, Philadelphia, Pa., assignor to Rosenau Bros. Inc., Philadelphia, Pa., a corporation of Pennsylvania

Original application May 24, 1937, Serial No. D. 69,511. Divided and this application July 3, 1937, Serial No. D. 70,258

Term of patent 3½ years

To all whom it may concern:

Be it known that I, Mary Mullen, a citizen of the United States, residing at Philadelphia, in the county of Philadelphia and State of Pennsylvania, have invented a new, original, and ornamental Design for an Ensemble Dress, of which the following is a specification, reference being had to the accompanying drawing, forming part thereof.

The present application is a division of my earlier-filed application, Serial No. D. 69,511, filed May 24, 1937.

I claim:

The ornamental design for an ensemble dress, as shown and described.

MARY MULLEN.
